UNITED STATES PATENT OFFICE.

JAMES W. CAMERON, OF NEW YORK, N. Y., ASSIGNOR TO DAVID J. BOEHM,
OF SAME PLACE.

MACHINE FOR CUTTING CIGAR-WRAPPERS.

SPECIFICATION forming part of Letters Patent No. 355,918, dated January 11, 1867.

Application filed November 28, 1885. Serial No. 184,182. (No model.)

To all whom it may concern:

Be it known that I, JAMES W. CAMERON, of the city, county, and State of New York, have invented a new and useful Improvement in 5 Machines for Cutting Cigar - Wrappers, of which the following is a full, clear, and exact description.

Reference is to be had to the accompanying drawings, forming a part of this specification, 10 in which similar letters of reference indicate corresponding parts in all the figures.

Figure 1 is a side elevation of a part of my improved machine, parts being broken away. Fig. 2 is a sectional end elevation of the same. 15 Fig. 3 is a plan view of the cutter and its elastic packing.

The object of this invention is to provide new and useful improvements in machines for cutting cigar-wrappers, whereby one leaf, or 20 from fifty to one hundred tobacco-leaves, called a "book," may be cut at one operation and without the aid of any sustaining devices for holding the leaves in place while being cut.

The invention consists in the construction 25 and combination of various parts of the machine, as will be hereinafter fully described, and specifically set forth in the claims.

A represents the frame of the machine, and B is the table attached to the top of the said 30 frame.

To the table B is secured the bed-plate C, in the upper side of which is formed a groove to receive the rear edge of the cutter D, which groove is made of the exact shape of the said 35 cutter, and the cutter is made of the exact shape of the required wrappers. The cutter D projects through a rubber packing-block, E, of a thickness equal to or a little greater than the height of the cutter D above the 40 bed-plate C, which block forms a table upon which the tobacco-leaf is laid, so that the said leaf can be readily adjusted. The upper edge of the cutter D is curved upon the arc of a circle, having its center in the axis of the vi- 45 brating bar F, so that the roller G, journaled to the forked upper end of the said vibrating bar, will move along the edge of the cutter D with a uniform pressure.

The roller G is made of a series of disks of 50 compressed leather, rawhide, paper, or other

suitable material, secured to a shaft by washers and nuts or other suitable means. The journals of the roller G revolve in bearings placed in the slotted upper ends of the branches of the bar F, and secured in place adjustably by 55 screws or other suitable means, so that the said roller can be readily adjusted to take up the wear. The arms of the bar F pass through and vibrate in slots in the table B, as shown in Fig. 2, and its lower end is pivoted to a pivot-pin, 60 H, secured to a base-bar of the frame A or other suitable support. The middle part of the vibrating bar F is slotted longitudinally to receive the crank-pin I or a sliding bearing, J, for the said crank-pin. The crank-pin I is 65 attached to the outer part of the large gear-wheel K, which is journaled in bearings attached to the frame A.

Into the teeth of the large gear-wheel K mesh the teeth of the pinion-wheel L, attached to the 70 shaft M, which revolves in bearings attached to the frame A, and to one of its ends is attached a crank-wheel, N, the crank-pin O of which serves as a handle for operating the machine. The crank-wheel N is made large and heavy, to 75 adapt it to serve also as a balance-wheel.

With this construction the machine is operated by turning the crank-wheel N, which vibrates the bar F and causes the roller G to move forward and back along the cutter D. 80 As the roller G moves off the end of the cutter D, the leaf of tobacco is adjusted to bring the part of the said leaf, from which the wrapper is to be cut, over the cutter D. As the roller G moves along the cutter D, it presses the leaf down 85 upon the edge of the cutter, and presses the rubber packing E below the said edge, so that the part of the leaf being cut will be fully supported while the cut is being made, and will thus be prevented from being torn. 90

I am aware that it is not new to provide a machine for cutting cigar-wrappers with a knife shaped to conform to the blank desired, and having a plate within the knife resting on spiral springs. The arm carrying the roller 95 was pivoted to swing in a horizontal line; also, that the roller has been journaled in fixed supports and the cutter secured to a vertically-vibrating arm operated by a treadle, and do not claim such as of my invention. 100

I am also aware that it is not new to have a vertically-swinging arm carrying a roller to bear on the knife, and I do not claim the same, broadly, as of my invention.

5 Having thus fully described my invention, I claim as new and desire to secure by Letters Patent—

1. In a cigar-blank cutter, the knife D, shaped to conform to the cigar-blank, and a rubber block, E, having a slot shaped to receive the knife, and inclosing its inner and outer sides, the cutting-edge of the knife being approximately flush with the upper surface of the rubber block, substantially as set forth.

15 2. The combination, with the knife support-

ing bed and the stationary knife D, having its upper edge curved in the arc of a vertical circle, of the arm F, vibrating in a vertical plane and journaled below the knife in the center of the arc of its curve, said arm being forked at its upper end, and the arms of the fork projecting upward on either side of the knife, and of a roller journaled in arms of said fork, which roller is carried over the face of the knife, substantially as herein shown and described. 20

JAMES W. CAMERON.
